US00D509858S

(12) **United States Design Patent** (10) Patent No.: **US D509,858 S**
 May et al. (45) Date of Patent: **** Sep. 20, 2005**

(54) **BLOCK**

(75) Inventors: **Jerry May**, Colden, NY (US); **Robert W. Salmon**, Buffalo, NY (US); **Carol D. Snyder**, East Aurora, NY (US)

(73) Assignee: **Mattel, Inc.**, El Segundo, CA (US)

(**) Term: **14 Years**

(21) Appl. No.: **29/182,054**

(22) Filed: **May 20, 2003**

(51) LOC (8) Cl. **21-01**

(52) U.S. Cl. **D21/499**

(58) Field of Search **D21/484-505, D21/398, 468-479, 483; D25/113, 118; 446/3, 8, 71, 75-77, 81, 85, 89-91, 97, 102, 117, 119-128, 168, 170, 227, 236, 243, 244, 265, 267, 297, 397, 404, 418, 419; 404/34, 19, 17, 29, 24, 27; 52/311.2, 390, 596, 604, 609; 434/156, 159, 167, 171, 172, 174, 188, 191, 205, 208, 403**

(57) **CLAIM**

The ornamental design for a block, as shown and described.

DESCRIPTION

FIG. 1 is a perspective view of a block;
 FIG. 2 is a front view of the block illustrated in FIG. 1;
 FIG. 3 is a rear view of the block illustrated in FIG. 1;
 FIG. 4 is a left side view of the block illustrated in FIG. 1;
 FIG. 5 is a right side view of the block illustrated in FIG. 1;
 FIG. 6 is a top view of the block illustrated in FIG. 1; and,
 FIG. 7 is a bottom view of the block illustrated in FIG. 1.
 The portion of the article depicted in broken lines is for
 illustrative purposes only and forms no part of the claimed
 design.
